FIRE EXTINGUISHER

Howard Waters Doughty, Amherst, Mass., assignor to Firetex Company, Attleboro, Mass., a corporation of Rhode Island

Application November 2, 1932, Serial No. 640,786

5 Claims. (Cl. 169—26)

This invention relates to fire extinguishers and particularly to a self-contained fire-extinguishing unit which is adapted to deliver automatically a liquid fire-extinguishing agent when the 5 temperature in the vicinity of the extinguisher rises to a predetermined point.

Extinguishers containing fire-extinguishing and pressure-generating agents are known and are in commercial use, notably apparatus described in Patent No. 1,698,840 issued to me. In that patent, it is pointed out that carbon tetrachloride and concentrated solutions of ammonia in water are among the most effective agents for use in fire extinguishers of the type 15 described. It is also shown that these liquids, in conjunction, exercise an extremely corrosive effect upon most ordinary metals, but that aluminum is not subject to such corrosion.

It is the object of the present invention to 20 provide further improvements in fire extinguishers wherein fire-extinguishing and pressure-generating agents are stored, and particularly to maintain such agents in separate compartments communicating with each other but normally 25 sealed so that communication is established only in the event that the fire-extinguishing liquid is to be released and ejected.

The separation of the fire-extinguishing and pressure-generating agents avoids any possibility 30 of corrosion, even though the receptacles for these agents are not resistant to the combined action thereof. The extinguisher is thus adapted particularly for use with carbon tetrachloride and aqueous ammonia solutions which jointly 35 corrode most metals other than aluminum. Other fire-extinguishing and pressure-generating agents may be used, however, in the extinguisher as hereinafter described.

In carrying out the invention, I provide a receptacle for the fire extinguishing agent with 40 an outlet having preferably a sprinkler head to distribute such agent over the area surrounding the extinguisher. The outlet may be controlled as shown in Patent No. 1,698,840. The details of the outlet and distributor may, however, be varied and may include the dual control features of Patents No. 1,736,255 and No. 1,736,256 issued to me. These features may be omitted if the particular advantages thereof are not desired.

I provide a separate receptacle for the pressure-generating agent outside the principal receptacle for the fire-extinguishing liquid. This 55 separate receptacle for the pressure-generating agent may be variously disposed at the bottom,

top or side of the principal receptacle, or it may wholly or partially surround that receptacle. A convenient arrangement is to place the receptacle for the pressure-generating agent at the bottom of the principal receptacle. It may, however, be arranged in the form of a coil surrounding the principal receptacle.

In any of these arrangements, I provide a communicating passage between the principal receptacle and the receptacle for the pressure-generating agent. This may be a pipe or merely an orifice or fitting, depending upon the arrangement selected. It should provide access for gas formed in the pressure-generating receptacle to the space above the liquid in the principal receptacle.

The passage or orifice or other means of communication is normally sealed. This may be accomplished by providing a cap or diaphragm which is held in place by a low melting point 75 solder adapted to be melted and therefore to release the pressure-generating agent when the temperature rises to a predetermined point. The cap or diaphragm also includes a portion which may be made of a frangible material such as 80 metal foil, aluminum, gold or silver foil for example, which is adapted to be ruptured when the pressure in the pressure-generating chamber rises to a predetermined point. The complete sealing is effected by a combination of these 85 devices so as to provide dual control, the gas being released only when both the temperature and pressure are above predetermined points to avoid possibility of premature entrance of gas under pressure into the receptacle for the fire- 90 extinguishing liquid.

In the apparatus as described, the fire-extinguishing and pressure-generating agents cannot mingle until the predetermined conditions requiring discharge of the fire-extinguishing liquid 95 prevail. Consequently there is no danger of corrosion due to the joint effect of these agents. Thus, carbon tetrachloride and aqueous ammonia solutions can be employed, even though the apparatus is constructed of metals other than those 100 which resist the joint action of these agents. Common metals such as iron, copper and brass may be used in constructing the apparatus, although it may also be made of aluminum, which has advantages owing to its high heat conductivity.

When the predetermined conditions arise, the pressure-generating agent releases gas and builds up the pressure. The gas under pressure is permitted to enter the space above the fire-extin- 110

guishing liquid when the seal between the two receptacles is broken through melting of the solder and rupture of the diaphragm. The fire-extinguishing liquid is ejected and sprayed over the surrounding surface if and when the seal in the sprinkler head is likewise released as the result of the increase in temperature. The fire-extinguishing liquid is thus sprayed over the surrounding surface and extinguishes the fire which caused the increasing temperature and the release of the liquid.

In the accompanying drawings, I have illustrated a typical example of an extinguisher embodying the invention. As hereinbefore noted, the particular arrangement of the parts is subject to numerous modifications, and the drawing is, therefore, not intended to limit the invention with respect to details. In the drawings;

Fig. 1 is a vertical section through the extinguisher;

Fig. 2 is a section on the line 2—2 of Fig. 1;

Fig. 3 is a vertical section through a modified form of extinguisher;

Fig. 4 is a section on the line 4—4 of Figure 3;

Figures 5 and 6 are details of modified forms of means for uniting and closing the passage between the receptacles for the two different liquids; and

Fig. 7 is a vertical section through the lower portion of an extinguisher having the sprinkler disposed at the bottom thereof.

Referring to the drawings, 5 indicates the principal receptacle which is substantially filled with the fire-extinguishing liquid, such, for example, as carbon tetrachloride 6. The principal receptacle may be constructed of any suitable metal or other material adapted to serve the purpose. A pipe 7 extends from a point near the bottom of the receptacle 5 through the top thereof to provide an outlet for the liquid contents. The outlet is normally closed by a cap which is adapted to be opened under fire temperature. This may comprise a diaphragm of metal foil 8 held in place by two washers mounted in a support 10 which is threadedly mounted on the end of the pipe 7, and the opening may be filled with low melting point solder 9, all as described in detail in my Patent No. 1,736,256. A deflector 11 is mounted on the support 10 to spread the fire-extinguishing liquid when it is ejected. The assembly, including the cap, fusible link and the support, constitute the usual type of sprinkler head and may be modified as desired, for example to include the control features of Patents No. 1,698,840 and No. 1,736,255.

At the bottom of the receptacle 5 I provide a second receptacle 12 which may be of smaller dimensions and also made of any suitable metal to hold the pressure-generating agent, such, for example, as an aqueous solution of ammonia. The receptacle 12 communicates with the interior of the receptacle 5 through a pipe 13, the upper end of which extends above the liquid level in the receptacle 5. The upper end of the pipe 13 is closed by a cap which includes a member 14 secured by easily fusible solder 15. The melting point of the solder should be such as to release the portion 15 of the cap when the temperature rises to the point at which discharge of the fire-extinguishing liquid is desired. Thus, in the event of a fire, the cap will be released and the gases generated by the rising temperature in the receptacle 12 will enter the receptacle 5, and upon release of the sprinkler head the fire-extinguishing liquid will be ejected.

The portion 14 of the cap may be of relatively thick metal or, if desired, it may be made of a comparatively thin metal foil, for example, aluminum, gold or silver foil of a thickness such that it will be ruptured when the pressure in the receptacle 12 and pipe 13 reaches a certain predetermined point. When the portion 14 of the cap is made of comparatively thin metal foil, it may be secured in place by extending it over the edges of the pipe 13 and pressing it into the threads on the upper end thereof as shown at 14'. The solder 15 may thereafter be threaded onto the threads over the metal foil which is pressed thereinto. In that case, when the temperature has increased sufficiently to melt the solder 15 and the pressure in the receptacle 12 and tube 13 increases sufficiently to rupture the portion 14 of the cap, the pressure-generating agent will be discharged into the upper portion of the receptacle 5 and may cause a discharge of the fire extinguishing fluid therefrom when a similar release occurs at the sprinkler head.

A removable plug 16 may be provided in the top of the receptacle 5 to permit refilling of the separate receptacles, and the replacement of the cap when it has been removed or ruptured in the operation of the apparatus. A suitable bail 17 or other support may be provided to facilitate placing the extinguisher in proper position for protection of surrounding surfaces. Obviously, the sprinkler head may be disposed at the bottom rather than at the top of the apparatus, in which case the pipe 7a extends from the interior of the receptacle 5 through the receptacle 12 at the bottom, but the pipe 7a does not, in this case, extend beyond the bottom of the receptacle 5, so that the liquid contents will be forced from the receptacle by the gas released from the receptacle 12.

In the extinguisher shown in Figure 3, the receptacle 20 for holding the solution of ammonia or other pressure-generating agent encircles the receptacle 21 for the carbon tetrachloride or other extinguishing liquid, and the two receptacles are connected by an external passage 22, 23. The two passages are connected by a union 24, 25. The threads 26 are left-hand threads and the threads 27 are right-hand threads, so that on turning the part 25 of the union (which may have an outer hexagonal cross-section to facilitate turning), the two passages are drawn together and a tight joint is formed. The two passages are separated by the diaphragm 28 which is of metal foil of such strength that it will be ruptured by the pressure produced in the outer receptacle 20 at fire temperature. The diaphragm is held in place by washers 29. The diaphragm keeps the two liquids from mixing. When the extinguisher is subjected to fire temperature, the pressure generated in the outer receptacle ruptures the diaphragm and the gas thus released forces the fire extinguishing liquid through the outlet tube 7'. It is ejected against the spray head 11 with sufficient force to spray it over the surroundings.

Modified and preferred means for uniting and closing the passage between the receptacles 20 and 21 are shown in Figures 5 and 6. Figure 5 includes a fusible plug 30 which may be formed by inserting a wooden plug in the opening 31 and pouring in solder which will be supported by the shoulders 32. After the solder has set, the wooden plug will be removed. The washer 33 will then be put into position and vaseline 34, or other suitable low melting material will be introduced into the cavity thus formed in sufficient amount to

just fill the space to the level of the washer 33. This serves as a support for the diaphragm 35 which is foil of any suitable metal. After placing the diaphragm in position the washer 36 5 is introduced and the union completed.

Figure 6 shows another form of fusible link in which a cap of solder 40 is soldered to the threaded metal tube 41. In other respects the coupling shown in Figure 6 is similar to that shown in 10 Figure 5. When the coupling is subjected to fire temperature the solder melts and the diaphragm is ruptured by pressure of the gas generated in the receptacle 20. The gas then escapes to the receptacle 21 and the carbon tetrachloride or 15 other extinguishing liquid is forced against the spray head 11', the diaphragm 8' and seal 9' being broken by the heat and pressure.

The various illustrations shown in the drawings suggest various modifications of structures which 20 may be utilized in keeping the liquids separate in extinguishers of the types shown in Figures 1 and 3.

As will be readily understood, the fire-extinguishing and pressure-generating agents are 25 maintained separately in the apparatus and cannot come together or mingle until conditions arise which require delivery of the fire-extinguishing liquid from the apparatus. No corrosion can occur, therefore, in the apparatus, even though 30 it is maintained without operation for long periods of time. Whenever the temperature rises sufficiently, as for example when a fire occurs, the gas generated in the pressure-generating chamber is promptly released and becomes available to 35 force the fire-extinguishing liquid from the apparatus.

Various changes may be made in the details of the construction and arrangement of the parts as hereinbefore indicated, without departing from 40 the invention or sacrificing any of the advantages thereof.

I claim:

1. A fire extinguisher comprising a closed principal receptacle for fire-extinguishing liquid, outlet means constructed and positioned to normally prevent discharge of the liquid therethrough and adapted to be open at predetermined fire temperature, an independent receptacle outside the principal receptacle adapted to hold a fluid capable of generating a gas under pressure when the temperature rises, a passage between the two receptacles, heat sensitive means, and additional means sensitive to pressure normally closing the passage and adapted to be opened when both said 55 heat and pressure sensitive means have operated.

2. A fire extinguisher comprising a closed principal receptacle for fire-extinguishing liquid, outlet means constructed and positioned to normally prevent discharge of the liquid therethrough and adapted to be open at predetermined fire tem- 60

perature, an independent receptacle outside the principal receptacle adapted to hold a fluid capable of generating a gas under pressure when the temperature rises, a passage between the two receptacles, and means normally closing the passage and adapted to be opened under the combined action of predetermined fire temperature and predetermined generated pressure including a diaphragm secured in place across said passage and a mass of low melting material which is solid at normal temperatures.

3. A fire extinguisher comprising a closed principal receptacle for fire-extinguishing liquid, outlet means constructed and positioned to normally prevent discharge of the liquid therethrough and adapted to be open at predetermined fire temperature, an independent receptacle outside the principal receptacle adapted to hold a fluid capable of generating a gas under pressure when the temperature rises, a passage between the two receptacles, and means normally closing the passage and adapted to be opened under the combined action of predetermined fire temperature and predetermined generated pressure including a frangible diaphragm secured in place across said passage and a mass of low melting material which is solid at normal temperatures.

4. A fire extinguisher comprising a closed principal receptacle for fire-extinguishing liquid, outlet means constructed and positioned to normally prevent discharge of the liquid therethrough and adapted to be open at predetermined fire temperature, an independent receptacle outside the principal receptacle adapted to hold a fluid capable of generating a gas under pressure when the temperature rises, a passage between the two receptacles, and means normally closing the passage and adapted to be opened under the combined action of predetermined fire temperature and predetermined generated pressure including a metal foil diaphragm secured in place across said passage and a mass of low melting material which is solid at normal temperatures.

5. A fire extinguisher comprising a closed principal receptacle for fire-extinguishing liquid, outlet means constructed and positioned to normally prevent discharge of the liquid therethrough and adapted to be open at predetermined fire temperature, an independent receptacle adapted to hold a fluid capable of generating a gas under pressure when the temperature rises, an external passage connecting the two receptacles and means normally closing the passage and adapted to be opened under the combined action of predetermined fire temperature and predetermined generated pressure including a diaphragm secured in place across said passage and a mass of low melting material which is solid at normal temperatures.

HOWARD WATERS DOUGHTY. 135
